MACHINE FOR FORMING SOLES

John M. Ewart, Beverly, Mass., assignor to United
Shoe Machinery Corporation, Flemington, N.J.,
a corporation of New Jersey

Application November 14, 1947, Serial No. 785,875

11 Claims. (Cl. 12—22)

1

This invention relates to machines for forming soles and is concerned particularly with the preparation of soles for their attachment to shoes by means of a cement.

In making a shoe of this type it is important that a secure and close attachment of the sole to the shoe bottom be obtained, especially along their margins. In the attainment of this requirement it is customary to impart a cupped formation to the sole by transversely curving its margin so that when the sole is applied to the shoe bottom, their surfaces having been coated with cement, the margin of the sole will tend to hug the shoe bottom. Such a condition insures effective adhesion as well as a close joint between the sole and shoe bottom at all points around the shoe.

It commonly happens, in thus forming a sole by the use of prior machines, that the sole is marred on the grain side by excessive pressure or rubbing of the operating members against it. In addition, the sole may also be so twisted that in pressing the sole against the shoe bottom the margin of the sole will buckle away from the shoe bottom as the twist is removed. Wherever such buckling occurs the sole margin springs away from the shoe bottom instead of lying closely against it as is desired.

In view of the foregoing, the principal object of the invention is to provide an improved machine for imparting the curvature to a sole margin, which is desired in connection with the cement sole attaching methods as outlined above, without otherwise deforming the sole as by twisting it and without marring its grain surface.

Other objects and the various features of the invention will appear from the following description of an illustrative machine embodying the invention and will be set forth in the appended claims.

In the drawings,

Fig. 1 is a side elevation of an illustrative machine embodying the invention;

Fig. 2 is a view in perspective, partly in section, of a sole which has been formed by the use of the machine;

Fig. 3 is a front elevation of the structure shown in Fig. 1;

Fig. 4 is a front elevation showing the operating members of Fig. 3 at an enlarged scale and operating upon a sole;

Fig. 5 is a plan view of the machine; and

Fig. 6 is an enlarged plan view of the operating members showing a sole being operated upon.

The illustrated machine comprises a pedestal

2

10 above the top of which a flat table 12 is mounted on a bracket 14, the bracket being secured to the pedestal by a screw 16. The rear right corner of the table is cut away as shown in Fig. 5 and is provided with a semi-circular recess within which closely fits a sole support 18 in the form of a disk, the upper radial surface of which is flush with the table. This disk is fixed to the upper end of a spindle 20 which is mounted to rotate freely about a vertical axis in bearings 22, 24 (Fig. 3) the latter bearing having a ball-thrust element for supporting the disk 18 vertically.

Cooperating with the disk 18 to impart a feed movement to a sole disposed between them is a feed wheel 26 having a narrow knurled periphery which is arranged to engage the sole along a narrow band spaced inwardly from its edge. The feed wheel is held by a screw 28 on the outer end of a shaft 30 which is mounted to rotate in a bearing member 32. Yielding movement of the feed wheel toward and from the disk 18 is provided by mounting the member 32 to pivot on a pair of trunnions 34 which are carried by lugs 36 extending upwardly from the top of the pedestal. For a portion of its length the bearing member 32 is bifurcated as shown in Fig. 5 and here closely receives a post 38 which braces the bearing member against lateral movement and has a clearance hole 40 through which the shaft 30 passes.

The lowermost position of the feed wheel 26, in which it just clears the disk 18, is determined by a plunger 42 which slides in and seats on the head of the pedestal 10. The feed wheel is yieldingly urged toward the disk by a coil spring 44, the lower end of which bears against the upper side of the bearing member 32, the compression of the spring being under the control of a knob 46 which engages the upper end of the spring 44 and is threaded in a projection 48 extending laterally from the post 38.

The feed wheel 26 is constantly rotated by connections comprising a pulley 50 which is fixed to the shaft 30 and is driven by a belt 52 which 45 may be driven from any suitable source such as a belt driven countershaft 54 as indicated in Figs. 1 and 3.

Cooperating with the feed wheel 26 to impart the desired concavity to the margin of a sole, as illustrated in Fig. 2, are a frusto-conical roll 56, and a projection 58 extending upwardly from the disk 18 and coaxially therewith. The roll 56 is freely rotatable upon a stud 60 which extends through a slot 62 in the table and which may be 55 clamped in any desired position along the slot

by setting up a nut 64 threaded on the lower end of the stud. To facilitate presenting a sole to the machine, the feed wheel can be elevated against the pressure of the spring 44 by operating a treadle (not shown) to which is connected a treadle rod 66. This rod and the lower end of the plunger 42 are pivotally connected by pins 68, 70 respectively to a lever 72 which itself is pivoted on a pin 74 carried by a projection 75 extending downwardly from the head of the pedestal 10. With the feed wheel 26 in an elevated position, the margin of a sole is inserted between it and the disk 18, the edge of the sole being in engagement at 76 (Fig. 4) with a guard 78 which is fixed to the end of the bearing member 32 adjacent to the feed wheel. The guard and bearing member are provided with a recess 80 into which the extremity of the projection 58 telescopes so that in the normal operation of the machine the guard presents a shoulder to the edge of the sole, which shoulder extends entirely around the projection. When the treadle is released a spring 82 which surrounds the plunger 42 moves the latter downwardly, permitting similar movement of the bearing member 32 under the pressure of the spring 44. The portion of the sole underneath the feed wheel 26 is thus brought to the level of the table 12, the margin of the sole being bent away from the table by the projection 58 and the body of the sole being bent away from the table by the roll 56. Different adjustments of the roll 56 along the slot 62 may be employed depending upon the amount of bending or cupping desired in the sole margin. By adjusting the knob 46 the compression in the spring 44 can be brought to an amount sufficient to cause the feed wheel 26 to flex the sole in the above described manner without pressing it with any substantial force against the radial surface of the disk 18. It will also be observed with reference to Fig. 4 that substantial areas of clearance above the sole at each side of the feed wheel insure against the sole being subjected to any molding action, as distinguished from purely bending, from either the projection 58 or the roll 56. Accordingly, any tendency for the grain (lower) side of the sole to be marred by pressure from the members which engage it is minimized; and the same end is furthered by the fact that both the roll 56 and disk 18 are rotated freely in response to the feeding movement of the sole and so cannot rub against or burnish the sole.

Referring now to Fig. 6 it will be noted that the bite of the feed wheel 26 and disk 18 is beyond, with regard to the direction of the feeding movement, a line between points on the roll 56 and projection 58 which are spanned by the sole. The effect of this relation is to cause the sole at and beyond the feed wheel 26 to be held down against the table 12 owing to the fact that the roll 56 and projection 58 lift the sole away from the table in advance of the feed wheel. This action on the sole materially aids in maintaining the generally flat condition of the sole lengthwise thereof while its margin is being formed or cupped.

This holding of the sole against the table as it passes beyond the feed wheel is furthered by a guide 84 which also is arranged to cooperate with the feed wheel 26 and the disk 18 to provide a cross-feed. The guide 84 is frusto-conical and is mounted on the table in an inverted position so that it presents an overhanging guiding surface to the edge of the sole. The guide is mounted

to rotate freely on a stud 86 which is fixed to one end of a bar 88. A bolt 90 which passes through a slot 92 in the bar and is threaded into the table 12 is adapted to secure the bar in any desired position of adjustment on the table. A typical arrangement of the guide 84 and feed roll 26 which provides a satisfactory feeding action is illustrated by Fig. 6 in which the feeding action of the feed wheel is directed obliquely across the sole margin toward the guide and along a line which passes between the guide and the projection 58. The feeding action thus tends to hold the edge of the sole against the guide 84 and the guard 78 simultaneously, and accordingly, the sole is caused to position itself automatically throughout the feeding action as is usual in this type of feed. It is further noted that the pressure of the sole against the guide 84 develops a wedging action between the sole and the overhanging surface of the guide which assists in holding the sole in this locality against the table.

As an operation upon a sole proceeds the sole is swung from one position to another on the table owing to the changing contour of that portion of the sole edge which is between the projection 58 and the guide 84. When a deeply concave portion of the sole edge, such as occurs in the shank near the ball line, approaches the projection 58 the swinging movement of the sole on the table becomes rather abrupt and is opposed to the feeding action. In order to prevent the sole at this time from being forced too hard against the guard 78, with the consequent danger of jamming, an auxiliary guide 94 is provided. This guide is in the form of a vertical finger which is not engaged by the sole while the convex portions of it are being operated upon. The guard is so positioned, however, as to be engaged by the edge of the sole well in advance of the projection 58 when a concave portion of the sole passes the projection 58; and at this time the guide 94 assists the guard 78 in resisting the thrust of the sole. The guard is mounted for adjustment axially of the feed wheel 26 on the projection 48 and is adapted to be secured thereon by a pair of screws 96 which pass through an elongated slot 98 in the guide and are threaded into the projection.

The operation and use of the machine will now be briefly summarized. Let it be assumed that the proper adjustments have been made as to the positions of the guide roll 84 and the bending roll 56, and that the knob 46 has been so adjusted that a sole to be operated upon will be held beneath the feed wheel 26 at the level of the table 12. It is understood that the sole, if it engages the radial surface of the disk 18, is pressed against the disk beneath the feed wheel with only a very light pressure which is insufficient to cause the sole to be marked upon its grain side.

A sole to be operated upon, a right sole for example, is presented to the machine by inserting its inside margin at the heel breast line between the constantly rotating feed wheel 26 and the disk 18. The sole at first is moved crosswise of the axis of the feed wheel until its edge is engaged by both the guide 84 and the guard 78. At this time, the forming of the margin of the sole by the projection 58 and roll 56, as well as the feeding movement of the sole, begins. Since the feeding action of the feed wheel is directed obliquely across the sole margin its component extending in the direction of the sole edge imparts the feeding movement to the sole, and the other component, per-

pendicular to the sole edge, causes the sole continuously to be held against the guide 84 and guard 78. As the forming of the sole proceeds, its margin and body portions in advance of the feed wheel are bent away from the table by the projection 58 and the roll 56 respectively. This bending of the sole, which primarily is for the purpose of imparting a transverse curvature to it, also causes the portion of the sole beyond the feed wheel to be held down against the table 12 whereby the sole is maintained in a straight condition lengthwise thereof at and for some distance beyond the locality where the transverse bending occurs. The guide 84 assists in thus holding the sole against the table because of its overhanging sole engaging surface which causes the sole to be wedged against the table in response to the lateral pressure of the sole edge against the guide.

The sole is swung as required by its changing contour to maintain contact at all times between the sole and the guide 84 and the guard 78. When a deeply concave portion of the sole edge, such as that just behind the inside ball line of a right sole, approaches the projection 58 the sole swings abruptly in a clockwise direction (Fig. 6). At this time the auxiliary guide 94 also engages the sole edge and resists the tendency of the sole to become jammed against the guard 78. When the next convex portion of the sole reaches the projection 58 the edge of the sole moves away from the auxiliary guide 94.

The operation upon a right sole is completed when the outside heel breast line is reached. At this time the machine may be treadled to raise the feed wheel 26 off the sole and to facilitate the removal of the sole from the machine by the operator.

A left sole is presented to the machine by inserting its margin at the outside heel breast line between the feed wheel and disk 18, the operation being similar to that already described in connection with a right sole and terminating at the inside heel breast line.

Having thus described my invention, what I claim as new and desire to secure by Letters Patent of the United States is:

1. In a machine for operating upon soles, a table, a rotating feed wheel, a support constructed and arranged to hold the portion of the sole beneath the feed wheel at the level of said table, bending members one at each side of said feed wheel, said members being constructed and arranged to act upon the body and the margin of the sole in advance of the bite of said feed wheel and support to bend the portions of the sole at each side of said feed wheel away from said table, a guide shaped and arranged to present an overhanging guiding surface to the edge of the sole beyond said feed wheel whereby the sole is held against said table, and means for operating said feed wheel to impart a feeding action directed obliquely across the sole margin toward said guide.

2. In a machine for operating upon soles, a table, a rotating feed wheel, a support constructed and arranged to hold the portion of the sole underneath the feed wheel at the level of said table, bending members one at each side of said feed wheel, said members comprising a roll and a projection on said support constructed and arranged to act upon the body and the margin of the sole respectively in advance of the bite of said feed wheel and support to bend the portions of the sole at each side of said feed wheel away from said table, a guide shaped and

arranged to present an overhanging guiding surface to the edge of the sole beyond said feed wheel whereby the sole is held against said table, and means for operating said feed wheel to impart a feeding action directed obliquely across the sole margin toward said guide.

3. In a machine for operating upon soles, a table, a feed wheel, a freely rotating support having a flat surface flush with said table and adapted to support a sole inwardly from its edge against the pressure of said feed wheel, means for bending away from said table the marginal and body portions of the sole in advance of the bite of said feed wheel and support at each side of said feed wheel whereby a transverse curvature is imparted to the margin of the sole, a guide shaped and arranged to present an overhanging guiding surface to the edge of the sole beyond said feed wheel whereby the sole is held against said table, and means for operating said feed wheel to impart a feeding action directed obliquely across the sole margin toward said guide.

4. In a machine for operating upon soles, a table, a rotating feed wheel, a freely rotatable member constructed and arranged to support a sole against said feed wheel at the level of said table and to bend the margin of the sole at one side of said feed wheel away from said table, a second member for bending the sole at the other side of said feed wheel away from said table, and a guide mounted on said table beyond the point of operation of said feed wheel and presenting an overhanging guiding surface to the edge of the sole whereby the sole is held against the table, said feed wheel being mounted and arranged to exert a feeding action directed obliquely across the margin of the sole toward said guide.

5. In a machine for operating upon soles, a table, a feed wheel, a freely rotatable member having a surface at the level of said table adapted to support a sole inwardly from its edge beneath said feed wheel, said member also having a projection for bending the outer margin of the sole at one side of said feed wheel away from said table, a second rotatable member for bending the sole at the other side of said feed wheel away from said table, a guide beyond the point of operation of said feed wheel having a sole edge engaging surface disposed at an acute angle to said table, and means for operating said feed wheel to provide a feeding action directed between said guide and said projection.

6. In a machine for operating upon soles, a table, a feed wheel, a freely rotatable disk having a flat sole supporting surface from which extends an axial projection arranged to bend the margin of a sole between said feed wheel and disk away from said table, a guard mounted adjacent to said projection for preventing the sole edge from rising off said projection, a guide having a sole edge engaging surface converging with said table, and means for operating said feed wheel to provide a feeding action exerted obliquely across the margin of the sole toward said guide.

7. In a machine for operating upon soles, a table, a feed wheel, a freely rotatable disk adapted to support a sole beneath said feed wheel at the level of said table and having an axial projection arranged to bend the margin of the sole toward said feed wheel, said feed wheel being mounted yieldingly to press the sole against said disk, a guard associated with said feed wheel and surrounding said projection at the side thereof

adjacent to said feed wheel, a guide mounted on said table and having a sole edge engaging surface converging with said table, and means for operating said feed wheel to exert a feeding action directed obliquely across the margin of the sole.

8. In a machine for operating upon soles, a table, a rotating feed wheel, a freely movable member constructed and arranged to support a sole beneath said feed wheel at the level of said table and to bend the margin of the sole extending outwardly thereof from said feed wheel away from said table, a roll mounted to rotate freely on said table and arranged to bend the body of the sole away from said table, a guide roll mounted on said table, said roll being shaped to present an overhanging surface to the edge of the sole whereby the sole is held against the table, said feed wheel being mounted and arranged to exert a feeding action on the margin of the sole directed obliquely across it toward said guide.

9. In a machine for operating upon soles, a table, a freely rotatable disk having a radial sole supporting surface flush with said table, a guide mounted on said table and having a sole edge engaging surface disposed at an acute angle to said table, a rotating feed wheel cooperating with said disk to exert on a sole therebetween a feeding action directed obliquely across the sole margin toward said guide, said disk having an axial projection arranged to bend the margin of the sole at one side of the feed wheel away from said table, and a frusto-conical roll at the other side of said feed wheel for bending the body of the sole away from said table.

10. In a machine for operating upon soles, a table, a frusto-conical roll, a rotating disk having a flat surface at the level of said table from which extends upwardly an axial projection, and

a rotating feed wheel cooperating with said disk to hold the sole inwardly from its edge at the level of said table whereby the marginal and body portions of the sole are bent about said feed wheel towards the sides thereof by said projection and roll respectively, said roll being mounted on said table for adjustment toward and away from said feed wheel.

11. In a machine for operating upon soles, a table on which a roll is mounted to rotate freely, a freely rotatable disk mounted flush with said table and having an axial projection extending upwardly therefrom, a rotating feed wheel cooperating with said disk to hold the sole inwardly from its edge at the level of said table whereby the marginal and body portions of the sole are bent toward the sides of the feed wheel by said projection and roll respectively, and a pair of guides adapted to engage the sole edge at localities beyond and in advance of said feed wheel.
